(57) **CLAIM**

The ornamental design of a sport trailer with open frame, as shown and described.

DESCRIPTION

FIG. 1 is a front perspective view of the sport trailer with open frame;

FIG. 2 is a back perspective view of the sport trailer with open frame;

FIG. 3 is a front elevation view of the sport trailer with open frame;

FIG. 4 is a back elevation view of the sport trailer with open frame;

FIG. 5 is a right side elevation view of the sport trailer with open frame;

FIG. 6 is a left side elevation view of the sport trailer with open frame;

FIG. 7 is a top plan view of the sport trailer with open frame; and,

FIG. 8 is a bottom plan view of the sport trailer with open frame.

In the drawings, the broken lines depict portions of the article that form no part of the claimed design.
